UNITED STATES PATENT OFFICE.

LAURENCE E. TOPHAM, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

DRIVING AND STOPPING MECHANISM.

1,099,328.

Specification of Letters Patent.

Patented June 9, 1914.

Application filed August 12, 1912. Serial No. 714,623.

To all whom it may concern:

Be it known that I, LAURENCE E. TOPHAM, a citizen of the United States, residing at Swampscott, in the county of Essex and State of Massachusetts, have invented 5 certain new and useful Improvements in Driving and Stopping Mechanism; and I do hereby declare the following to be a full, clear, and exact description of the invention, 10 such as will enable others skilled in the art to which it appertains to make and use the same.

The invention relates to driving and stopping mechanism adapted for use in high 15 speed machines.

The object of the invention is to provide novel and improved mechanism by which a machine or mechanism which is normally driven at a high speed may be stopped in a 20 certain and reliable manner at a predetermined point in its cycle of operations without undue shock and wear upon the parts.

With this object in view the invention 25 contemplates the provision of a mechanism for driving a machine or mechanism at a high speed during its normal operation, and a slow speed driving mechanism which is thrown into operation just before the machine is to be stopped, and which first acts

30 as a brake to slow down the machine, and then acts to drive the machine at a predetermined slow speed to stopping position.

In the preferred form of the invention the 35 slow speed driving mechanism comprises a friction brake which is engaged at a predetermined time in the cycle of operations of the driven machine to slow down the machine and then drive it at a uniform slow speed, and which is disengaged when the

40 machine is brought to stopping position. The driving member of the slow speed clutch may be driven in either a forward or reverse direction, and in either case acts as a friction brake to gradually reduce the

45 speed of the driven parts until the slip between the members ceases, after which it either continues the forward motion of the machine or turns it back at a uniform reduced speed to stopping position. The

50 means for throwing the slow speed clutch into operation is preferably automatic in its action, and is under the control of the operator through mechanism by which he may

at will throw the high speed mechanism out of action and render the mechanism for throwing in the slow speed clutch active.

The invention also includes certain further features of construction and combinations of parts which are hereinafter described and set forth in the claims.

The invention will be readily understood from an inspection of the accompanying drawings and the following detailed description of the construction illustrated therein.

In the drawings, Figure 1 is an elevation showing a side view of a machine embodying the invention in its preferred form; Fig. 2 is a similar view of the head of the machine with the parts in the position 70 which they occupy after the machine is brought to rest; Fig. 3 is a vertical sectional elevation through the axis of the cam shaft of the machine, the parts being in the same position indicated in Fig. 2; Fig. 4 is a 75 horizontal view partly in section with the parts in the same position; Fig. 5 is a sectional elevation on line 5—5 of Fig. 4, looking toward the left; Fig. 6 is a sectional elevation on line 6—6 of Fig. 4, looking 80 toward the right; and Fig. 7 is a detailed rear view looking toward the right in Fig. 6.

In the drawings the invention is illustrated as embodied in a welt and turn sewing machine such as shown and described in the 85 application of Andrew Eppler, Serial No. 447,542, filed August 8, 1908, and the slow speed driving mechanism and the mechanism for controlling its operation are constructed and arranged to reverse the cam 90 shaft in stopping the machine, so that the needle is retracted while its hook is empty and is brought to rest in position where it does not interfere with the removal of the shoe. It will be understood, 95 however, that the mechanism illustrated, as well as the invention embodied therein, is not confined in its application to a machine of this character, but may be used in other machines and in other relations.

The machine shown is provided with the usual stitch forming and work guiding and feeding devices, which are not shown in the drawings, and these devices are operated through suitable connections by cams carried by the cam shaft 6 of the machine. As

is usual in this type of machine, the cam shaft makes one revolution for each cycle of operations performed by the stitch forming and work feeding devices.

- 5 During the operation of the machine it is driven through a belt pulley 7 secured to the end of the cam shaft, and connected by a driving belt 8 with a pulley 9 mounted in the base of the machine. The pulley 9 is
10 connected through bevel gears 10 with a sleeve 11 mounted on the driving shaft 12 and carrying one member 13 of the main driving clutch. The driving shaft carries the other member 14 of the clutch, and also
15 carries the driving pulley 15 through which motion is imparted to the driving shaft. The engagement of the members of the driving clutch is controlled through a treadle 16 connected with the clutch operating wedge
20 17. When the treadle is depressed, the members of the driving clutch are forced into engagement, and the machine is driven at a speed depending upon the pressure which the operator applies to the treadle.
25 When the treadle is released the clutch members are disengaged, thus disconnecting the cam shaft of the machine from the driving shaft. The upward movement of the treadle when it is released also throws into operation
30 the slow speed driving and stopping mechanism. This mechanism, in the construction shown, comprises a reversely driven friction clutch consisting of the clutch members 18 and 18'. The clutch member 18 is formed
35 on a spiral gear 19 which is loosely mounted on the cam shaft 6, and is driven in a direction opposite to the direction of rotation of the cam shaft during the sewing operation by a spiral pinion 20 secured to a shaft 21.
40 The shaft 21 is continuously driven from the driving pulley 15 through a belt 22 passing over a pulley formed on the hub of the pulley 15, and over a pulley 23 secured to the shaft 21. The other member of the
45 clutch 18' is formed on a flange 24 projecting from a sleeve 25 which is loosely mounted upon the cam shaft 6. The sleeve 25 is free to slide longitudinally on the shaft, but is connected to rotate with the shaft by
50 means of a block 26 secured to the pulley 7 and arranged between lugs 27 projecting radially from the sleeve 25. The sleeve is held normally in position with the clutch members out of engagement by a spring 28
55 arranged in a recess in the block 26 and interposed between the bottom of the recess and the head of a bolt which carries a plate 29 engaging the lugs 27. The normal position of the clutch sleeve is determined by
60 an adjustable stop screw 30 which may be adjusted to maintain the clutch sleeve in proper relation to the clutch member. When the clutch members 18 and 18' are engaged, they act as a frictional brake to absorb the
65 energy due to the momentum of the cam

shaft, and after the forward movement of the shaft has ceased the clutch acts to turn the cam shaft in a reverse direction at a comparatively slow speed until the clutch is disengaged, when the cam shaft is brought 70 to rest with the needle and other parts of the stitch forming mechanism in the proper position for the removal of the shoe.

The mechanism for engaging and disengaging the clutch at the proper times in 75 the rotation of the cam shaft comprises a cam groove 31 formed in the sleeve 25 and engaged by a roll on one arm of a bell crank lever 32. The other end of the bell crank lever is provided with a hole 33 adapted to receive a coupling device in the form of a pin 34 which is normally held out of engagement with the lever, so that during the normal running of the machine the lever is 80 oscillated idly by the cam. The pin is mounted in the end of a slide 35 which is held in normal position by a spring 36. The spring surrounds a bolt 37 extending from the rear end of the slide, and is interposed 85 between a shoulder on the slide and the inner end of an adjustable screw threaded sleeve 38. The bolt 37 carries a nut 39 which engages the outer end of the sleeve and holds the spring under tension. By adjusting the nut the tension of the spring 90 may be varied, and by adjusting the sleeve 38 the slide may be adjusted to bring the coupling pin into proper register with the hole in the end of the lever 32. The pin is forced in a direction to engage it with the bell crank lever by a spring 40, and the lower end of the pin is connected with the treadle 16 so that the pin is held down out of 95 engagement with the bell crank lever so long as the treadle is depressed and the main 100 driving clutch is acting to drive the cam shaft of the machine. A latch 41 is also connected with the lower end of the coupling pin, and is arranged to engage a shoulder 42 on the slide 35, and hold the pin in its lower 105 position until the treadle has been raised sufficiently to allow the pin to engage the bell crank lever. In the construction shown, the latch 41 is loosely pivoted on a rock shaft 43, and is connected with the shaft by 110 a pin 44 projecting through a slot in the hub of the latch (Figs. 4 and 5). The rock shaft 43 is mounted in a block 45 secured on the lower end of the coupling pin, and carries an 115 arm 46 which is connected by a link 47 with the treadle 16. When the treadle is depressed the rock shaft 43 turns until the latch 41 brings up against the slide 35, and then during the continued downward movement of the treadle the coupling pin is 120 drawn down against the tension of its spring. This carries the latch 41 under the shoulder 42. When the treadle is released the latch 41 prevents the upward movement 125 of the pin, and the rock shaft 43 is rocked 130

until the pin 44 strikes the end of the slot in the hub of the latch and swings the latch outward, thus disengaging it from the shoulder 42. When this takes place the 5 spring forces the pin upward against the under side of the bell crank lever, and when the hole in the lever registers with the pin the pin snaps up into the hole, thus connecting the lever with the slide 35. The cam 31 10 is so timed that the hole in the end of the bell crank lever is brought into position to register with the coupling pin at the proper time in the cycle of operations of the stitch forming mechanism. When the pin is engaged 15 with the bell crank lever the lever is held from movement about its pivot, and the cam 31 acting on the roll carried by the lever, shifts the clutch sleeve 25 to bring the members of the reversing clutch into engagement. When the lever and slide 35 are connected by the coupling pin, the movement of the lever is resisted by the spring 36, and the force with which the members of the friction clutch are pressed together will depend 20 upon the tension of the spring. This may be adjusted to secure the desired braking effect between the members of the friction clutch so that the forward rotation of the cam shaft will be arrested without undue shock 25 or jar and within the desired part of a revolution. In the construction shown, the parts are so timed and controlled that the coupling pin is engaged with the lever and the friction clutch engaged while the needle is 30 retracted, and just before it begins its advance movement, and the forward rotation of the cam shaft is arrested after the needle has advanced and entered the work. The clutch then acts to turn the cam shaft in a 35 reverse direction at a slow speed until the shaft arrives at the point where the cam 31 acted to engage the members of the clutch, when the reversely moving cam acts to again disengage the clutch members. The cam 40 shaft is therefore brought to the desired stopping position after the momentum of the machine has been gradually overcome by the slip between the members of the clutch at a predetermined slow speed which 45 is unaffected by the speed of the machine at the time the main driving clutch is disengaged. When the reversing clutch is disengaged, the reverse movement of the cam shaft may be finally stopped by a friction 50 brake applied to one of the cam disks on the shaft, or by a positive stop, or both means may be employed, in which case the positive stop acts as a safety device to prevent any 55 accidental overrunning of the cam shaft. In 60 the construction shown, both devices are employed. As shown, the stop comprises a stop arm 48 secured to a rock shaft 49 and having its end arranged to be moved into and out of the path of a stop shoulder 50 on a cam 65 disk 51 which is secured to the cam shaft.

The rock shaft 49 is the shaft which is actuated by the reversal of the cam shaft to throw off the thread tension in the machine of the Eppler application above referred to. This shaft carries an upwardly projecting 70 arm 52, to the upper end of which is pivotally connected the actuating lever 53. The front end of the lever is provided with two segmental surfaces, the upper one of which runs against a sleeve on the cam shaft during the forward rotation of the cam shaft. With the lever in this position, the stop 48 is out of the path of the shoulder 50. When the rotation of the cam shaft is reversed, a notch in the sleeve acts on the lever 53 and 75 rocks it into the position indicated in Fig. 6, thus rocking the shaft 49 to throw off the thread tension, and also to bring the stop arm 48 into the path of the shoulder 50.

As shown, the friction brake which is applied when the slow speed clutch is disengaged comprises a brake strap 54 arranged to partially surround a disk 55 on the cam shaft. The front end of the brake strap is secured to a fixed stud 56, and the rear end 80 is connected to the upper end of the arm 52 so that the brake is applied when the shaft 49 is rocked at the completion of the reverse movement of the cam shaft. In order that the brake may be relieved before the machine 85 is started, means are provided for relieving the tension on the brake strap which are operated by the depression of the treadle. In the construction shown the rear end of the brake strap surrounds an eccentric drum 90 95 100 105 110 115 formed on the end of a rock shaft 58 which is journaled in the end of the arm 52. The other end of the rock shaft carries an arm 59 which is slotted to receive a pin 60 projecting from the stud 61 which forms the pivotal connection between the link 47 and the arm 46. When the treadle is depressed to start the machine, the link 47 is drawn downward in the manner already described, and the pin 60 acting in the slot of the arm 59 rocks the shaft 58 to relieve the pressure of the brake band upon the disk 55. The brake therefore offers no resistance to the rotation of the machine when the main driving clutch is engaged.

While in the construction described the driving member of the slow speed clutch is driven in a reverse direction so that the cam shaft of the machine is reversed in stopping the machine, substantially the same 120 mechanism may be employed for bringing the cam or driving shaft of a sewing or other machine into stopping position without reversing the shaft. In such case the driving member of the slow speed driving clutch will 125 be driven in a forward direction, as, for instance, by connecting the pulleys 7 and 9 by an open instead of a cross belt. In this case the clutch members when engaged will act as a friction brake to absorb the energy due 130

to the momentum of the shaft 6 until the shaft is rotating at the same speed as the clutch member 18, after which the shaft will be driven forward at a predetermined low speed by the clutch until the clutch is disengaged. In this case the timing cam 31 engages the members of the slow speed clutch at a predetermined point in the rotation of the cam shaft, and at a point sufficiently in advance of the point where the shaft is to be stopped, to insure a proper braking interval and gradual slowing down of the shaft before it is brought into stopping position. The proper braking and slowing down of the shaft without undue shock or jar is therefore insured, and the shaft is uniformly driven at the speed of the slow speed clutch into stopping position regardless of the speed of the machine at the time that the main driving clutch is disengaged.

Having explained the nature and object of the invention, and specifically described one form of mechanism in which it may be embodied, what is claimed is:—

25 1. A driving and stopping mechanism, having, in combination, a shaft, high and low speed driving mechanisms therefor, means under the control of the operator for shifting to the low speed driving mechanism at 30 a certain predetermined time in the rotation of the shaft, and means for stopping the shaft while it is being driven by the low speed mechanism.

35 2. A driving and stopping mechanism, having, in combination, a shaft, high and low speed driving mechanism therefor, means under the control of the operator operating automatically to shift to the low speed driving mechanism at a certain predetermined time in the rotation of the shaft, and means for stopping the shaft while it is being driven by the low speed mechanism.

40 3. A driving and stopping mechanism, having, in combination, a main driving mechanism and reverse low speed driving mechanism constructed to first act as a friction brake to gradually arrest the forward movement of the driven parts, and to then drive them at a slow speed back to stopping 50 position.

45 4. A driving and stopping mechanism, having, in combination, a shaft, a high speed driving mechanism therefor under the control of the operator, a low speed friction clutch, and means acting automatically when the high speed mechanism is thrown out by the operator to engage the clutch at a predetermined point in the rotation of the shaft and to disengage the clutch when the shaft 55 is brought to stopping position.

50 5. A driving and stopping mechanism, having, in combination, a shaft, a high speed driving mechanism therefor, a low speed reversing friction clutch, and means for en-

gaging the clutch at a predetermined point 65 in the rotation of the shaft and for disengaging the clutch when the shaft is brought to stopping position.

6. A driving and stopping mechanism, having, in combination, a shaft, main driving mechanism therefor, low speed driving mechanism having provision for frictionally resisting the forward movement of the shaft when thrown into operation, means under the control of the operator for throwing the slow speed driving mechanism into operation at a predetermined point in the rotation of the shaft, and means for throwing the low speed driving mechanism out of operation and stopping the shaft at a predetermined point.

7. A driving and stopping mechanism, having, in combination, a shaft, a main driving mechanism therefor, reverse driving mechanism having provision for frictionally resisting the forward movement of the shaft when thrown into operation, and means for throwing the reverse driving mechanism out of operation and stopping the shaft at a predetermined point in its reverse movement.

8. A driving and stopping mechanism, having, in combination, a shaft, high speed driving mechanism therefor, braking and low speed driving mechanism, means for throwing the braking and low speed driving mechanism into and out of operation including a timing cam, a lever normally engaging the cam, and means for rendering said cam and lever active when the main driving mechanism is thrown out of operation.

9. A driving and stopping mechanism, having, in combination, a shaft, high speed driving mechanism therefor, a braking and reverse driving mechanism, means for throwing said braking and reverse driving mechanism into and out of operation including a timing cam, and means for rendering said cam active when the main driving mechanism is thrown out of operation.

10. A driving and stopping mechanism, having, in combination, a shaft, a high speed driving mechanism therefor, a low speed driving mechanism having provision for frictionally resisting the forward movement of the shaft when thrown into operation, means for throwing said low speed driving mechanism into and out of operation including a timing cam and a normally inactive actuating lever normally engaging the cam, and means for rendering said lever and cam active when the high speed driving mechanism is thrown out.

11. A driving and stopping mechanism, having, in combination, a shaft, a high speed driving mechanism therefor, a reversely driven low speed friction clutch, devices driven from the shaft for engaging and dis-

engaging the clutch, and means for rendering said latter devices active when the high speed driving mechanism is thrown out.

12. A driving and stopping mechanism, having, in combination, a shaft, driving mechanism therefor including a starting and stopping treadle, a low speed clutch comprising a friction clutch member connected to rotate with the shaft, a cam driven by the shaft, an actuating lever operated by the cam, and a coupling device operated by the treadle for rendering the lever and cam active to engage the low speed clutch when the treadle is actuated to stop the shaft.

13. A driving and stopping mechanism, having, in combination, a shaft, a treadle controlled driving mechanism therefor, a low speed friction clutch one member of which is connected to rotate with the shaft, a cam on the clutch member, an actuating lever operated by the cam, a spring slide, and a coupling pin operated by the treadle for connecting the slide and lever when the treadle is actuated to throw out the driving mechanism.

14. A driving and stopping mechanism, having, in combination, a shaft, main driving mechanism therefor, a low speed friction clutch member mounted on the shaft, a co-operating clutch member connected to rotate with the shaft, a cam connected with the shaft, and devices rendered active upon the throwing out of the driving mechanism for co-operating with the cam in engaging and disengaging the clutch members.

15. A driving and stopping mechanism, having, in combination, a shaft, a treadle

controlled driving mechanism therefor, a low speed friction clutch member mounted on the shaft, a co-operating friction clutch member connected to rotate with the shaft, a cam on the latter clutch member, a lever operated by the cam, a spring slide, and a coupling device operated by the treadle for connecting the lever and slide.

16. A driving and stopping mechanism, having, in combination, a shaft, a treadle controlled driving mechanism therefor, a low speed friction clutch one member of which is connected to rotate with the shaft, means for engaging and disengaging the clutch including a timing cam driven from the shaft, a friction brake, means for applying the brake when the friction clutch is disengaged, and means operated by the treadle for releasing the brake in starting the driving mechanism.

17. A driving and stopping mechanism, having, in combination, a shaft, a treadle controlled driving mechanism therefor, a low speed friction clutch, mechanism for engaging and disengaging the clutch comprising a cam driven by the shaft, a lever operated by the cam, and a coupling pin for engaging the lever, and devices connecting the coupling pin with the treadle comprising a latch for preventing the engagement of the pin with the lever during the initial movement of the treadle.
